UNITED STATES PATENT OFFICE.

AUGUST D. COOK, OF LAWRENCEBURG, INDIANA.

DESIGN FOR A WELL-STRAINER.

SPECIFICATION forming part of Design No. 26,776, dated March 16, 1897.

Application filed January 7, 1897. Serial No. 618,420. Term of patent 14 years.

To all whom it may concern

Be it known that I, AUGUST D. COOK, a citizen of the United States, residing at Lawrenceburg, in the county of Dearborn, State of Indiana, have invented and produced a new and original Design for Well-Strainers, of which the following is a specification, reference being had to the accompanying drawings, showing a part thereof.

10 Figure 1 is a perspective view of a well-strainer, showing my design. Fig. 2 is a vertical sectional view of the strainer-wall exaggerated. Fig. 3 is a transverse sectional view of the strainer, the section being taken 15 through the openings or slits, these views being deemed sufficient to illustrate my invention.

15 The leading feature of my design consists in a series of vertical rows of transversely-disposed elongated openings or slits formed in the strainer, which, as is well known, is of a general tubular shape, such slits or elongated openings being formed at a substantial

right angle to the wall of the strainer and extending to a depth of about three-fourths 25 of the thickness of said wall, at which point the walls or surfaces of the said openings are gradually enlarged or flared on curved lines to the inner surface of the wall of the strainer.

20 A represents the wall of the strainer, and B the straight portion of the elongated slits or openings, the upper and lower surfaces of which are parallel for a depth of about three-quarters of the thickness of the wall of the strainer, and beyond said point the inner 35 ends of said openings or slits are gradually flared on curved lines, as at C.

What I claim is—

25 The design for well-strainers herein shown and described.

30 In testimony whereof I affix my signature in presence of two witnesses.

40 AUGUST D. COOK.

Witnesses:

CHARLES L. SKINNER,
WILLIAM F. COOK.
